UNITED STATES PATENT OFFICE

CHARLES HALDER, OF HAWTHORNE, NEW JERSEY, ASSIGNOR TO THE BRADFORD CORPORATION, OF NEW YORK, N. Y., A CORPORATION OF DELAWARE

STEAM LOCOMOTIVE

Application filed November 26, 1928. Serial No. 321,800.

The present invention relates to steam locomotives, and more particularly to improved means for delivering steam, from the boiler, to the working cylinders of a locomotive.

Heretofore, in locomotives embodying at least two high pressure working cylinders, the steam has been delivered from the boiler to the working cylinders by means of branch pipes, each leading through the smoke box, one for the left hand working cylinder, and another for the right hand working cylinder. In one well-known type of construction, the branch pipes are connected to suitable outlets in the superheater, while, in another well-known type of construction, in which the throttle valve is disposed forwardly of the superheater, the branch pipes are connected to suitable outlets in the throttle valve.

An object of the present invention is to provide an improved form of construction whereby a material reduction in the amount of piping and the number of pipe joints is effected, with a consequent substantial reduction in the weight of the locomotive, and a greater efficiency of forced draft. Another object, is to provide a construction requiring but a single opening through the smoke box for steam piping. A further object is to decrease to a minimum the volume of the steam passage between the throttle valve and the cylinders. Another object, is to provide a simpler, more compact, and more durable construction, whereby a substantial economy in installation and maintenance costs is effected, and greater efficiency in operation is assured. Other objects of the invention will hereinafter readily appear.

In the accompanying drawings: Figure 1 is a side elevation, partly in section, of the forward end of a locomotive embodying my invention; and, Fig. 2, a transverse, vertical section, taken on the line A A, Fig. 1, looking in the direction of the arrows.

In the practice of the present invention, referring descriptively to the specific embodiment thereof, which is herein exemplified, the locomotive comprises a boiler, 10, a smoke box, 11, a pair of side frame members 50 11^a, a superheater, 12, a pair of working cylinders, 13, a distribution valve chest, 14, for each working cylinder, and a piston valve, 15, in each distribution valve chest.

A single throttle valve, 16, for controlling the admission of steam to both of the distribution valve chests is mounted on the right hand valve chest, and disposed outside of the smoke box and outside of the adjacent side frame member 11^a. While the type of throttle valve may be varied as desired, for purposes of illustration, it has been shown as the combined disc and balancing piston type, adapted to be operated from the engineer's station by any suitable mechanism. 55

A single steam pipe, 17, is provided for conducting steam from the superheater, 12, to the throttle valve, 16. This pipe passes through a single opening, 18, in the smoke box wall. A sleeve, 19, of usual type, is provided to form a flexible air tight connection between the steam pipe and the smoke box wall. 60

A steam passageway, 20, leads from the right hand distribution valve chest, to the 75 left hand distribution valve chest, for supplying steam to the latter.

In the construction illustrated in the drawings, each of the working cylinders, its companion distribution valve chest, and one half 80 of the cylinder saddle 21 are formed as a single or integral casting. The steam passageway, 20, is formed in the integral castings, being so disposed as to pass through the cylinder saddle. It is to be understood 85 that the working cylinders, distribution valve chests, cylinder saddle, and the steam passageway may be integral or formed in various other ways, as desired, and that the steam passageway, 20, may be an independ- 90

ent pipe disposed outside of the smoke box and leading from one distribution valve chest to the other, or from a position in the passageway for supplying steam to the distribution valve on one side of the locomotive to a distribution valve disposed in a different vertical plane.

It is also to be particularly noted that the invention has application to any type of locomotive embodying two or more high pressure working cylinders.

It is further to be noted that instead of locating the throttle valve adjacent one of the distribution valve chests, it may be disposed adjacent the superheater, in the superheater, in the steam dome of the locomotive, or otherwise, as desired. The casing of the throttle valve may be made integral with the cylinder and distribution valve chest.

One of the important novel features of the present invention is the provision of a single steam supply pipe passing through the smoke box wall, for supplying steam to two or more high pressure cylinders, whereby the number of openings required in the smoke box wall is reduced to a minimum. Another novel feature of the invention is the substantial reduction in the amount of piping and the number of pipe joints, required to conduct the supply of steam for two or more high pressure working cylinders, whereby a material reduction in the weight of the locomotive is effected, and greater efficiency of forced draft assured. A further novel feature of the invention is the reduction to a minimum of the volume of the steam passageway between the throttle valve and the working cylinders. A further novel feature of the invention is the formation in the cylinder saddles of the steam supply passageway from one high pressure cylinder to another. Another novel feature of the invention is the placing of the throttle valve at a position where it is conveniently accessible for inspection and repair. A further novel feature of the invention is the placing of the throttle valve, its operating mechanism, and the steam supply pipe, on the opposite side of the locomotive from the air compressors, feed water heater pumps, and other accessories, whereby the weight of such accessories is counterbalanced.

Where the two cylinders are made identical the opening on one side is used for the steam inlet from the throttle valve and the opening on the other side may be used for a connection to a locomotive booster or auxiliary.

The invention claimed, and which it is desired to secure by Letters Patent, is:

1. In a locomotive, the combination of a boiler, a cylinder saddle, a smoke box, a plurality of working cylinders, a distribution valve chest for each of the cylinders, a single passageway, passing through the smoke box wall, and adapted to conduct through said

wall a supply of boiler steam for at least two of the working cylinders, said passageway leading to one of the distribution valve chests only, a throttle valve disposed in said passageway and outside of the smoke box, and a second passageway leading from the first mentioned valve chest through the cylinder saddle to another of the valve chests for conducting the supply of working steam thereto.

2. In a locomotive, the combination of a boiler, a smoke box, a plurality of working cylinders, a distribution valve chest for each of said cylinders, a single passageway, passing through the smoke box wall, and adapted to conduct through said wall a supply of boiler steam for at least two of the working cylinders, said passageway leading to one of the distribution valve chests, a throttle valve in said passageway disposed outside of the smoke box and at a position to one side of the longitudinal central vertical plane thereof permitting unobstructed access for inspection and repair, a second passageway, communicating with the first passageway at the delivery side of said throttle valve, and communicating with another of said distribution valve chests.

3. In a locomotive, the combination of a boiler, a smoke box, a plurality of working cylinders, a distribution valve chest for each of the cylinders, a single passageway, passing through the smoke box wall, and adapted to conduct through said wall, a supply of steam for at least two of the working cylinders, said passageway leading to one of the distribution valve chests, a throttle valve in said passageway, disposed outside of the smoke box, and a position to one side of the longitudinal vertical plane thereof permitting unobstructed access for inspection and repairs, and a second passageway leading from the first mentioned distribution valve chest to another of the distribution valve chests.

4. In a locomotive, the combination of a boiler, a superheater, a plurality of working cylinders, a distribution valve chest for each of said cylinders, a passage adapted to conduct the entire steam supply for said cylinders, connected with the superheater and one of the valve chests, a throttle valve in said passageway disposed outside of the smoke box and to one side of the longitudinal vertical plane thereof, and a passageway connecting said last mentioned valve chest to another of the valve chests.

5. In a locomotive, the combination of a boiler, a smokebox, a plurality of working cylinders, a distribution valve chest for each of the cylinders, a single passageway, passing through the smoke box wall, and adapted to conduct through said wall, a supply of steam for at least two of the working cylinders, said passageway leading to one of the distribution valve chests, a throttle valve in

5 said passageway disposed outside of the smoke box and supported on the top of one of the valve chests, and a second passageway leading from the first mentioned distribution valve chest to another of the distribution valve chests.

6. In a locomotive, the combination of a boiler, a smoke box, a plurality of working cylinders, a distribution valve chest for each cylinder, a single passageway leading through a side of the smoke box and having an effective cross sectional area adapted to conduct a supply of boiler steam for at least two of the working cylinders, and a throttle valve controlling the passage of steam through said passageway, disposed outside of the smoke box and at a position to one side of the vertical longitudinal plane thereof permitting unobstructed access for inspection and repairs.

7. In a locomotive, the combination of a boiler, a smoke box, a plurality of cylinders, a distribution valve chest for each cylinder, a throttle valve disposed outside of the smoke box and to one side of the vertical longitudinal plane thereof, a first boiler steam passageway leading to the throttle valve and having an effective cross sectional area adapted to permit the passage of an adequate supply of boiler steam for at least two cylinders, a second boiler steam passageway leading from the throttle valve to one of the distribution valve chests, and a third boiler steam passageway communicating with the throttle valve and another of the valve chests.

8. In a locomotive, the combination of a boiler, a smoke box, a pair of high pressure working cylinders, a distribution valve chest for each cylinder, a throttle valve disposed outside of the smoke box and to one side of the vertical longitudinal plane thereof, a first boiler steam passageway leading to the throttle valve and having an effective cross sectional area adapted to permit the passage of an adequate supply of boiler steam for at least two cylinders, a second boiler steam passageway leading from the throttle valve to one of the distribution valve chests, and a third boiler steam passageway communicating with the second passageway and another of the valve chests.

9. In a locomotive, the combination of a boiler, a smoke box, a plurality of working cylinders, a distribution valve chest for each cylinder, a throttle valve disposed outside of the smoke box and to one side of the vertical longitudinal plane thereof, a first boiler steam passageway leading through the smoke box to the throttle valve, and having an effective cross sectional area to permit the passage of an adequate supply of boiler steam for at least two cylinders, a second boiler steam passageway leading from the throttle valve to one of the distribution valve chests, and a third boiler steam passageway leading from

the last mentioned distribution valve chest to another of the valve chests.

10. In a locomotive, the combination of a smoke box, a source of pressure fluid, a plurality of cylinders adapted to receive pressure fluid from said source, distribution valves, controlling the flow of pressure fluid to said cylinders, valve chests for said valves, a passage connecting the source of pressure and one of said valve chests, a throttle valve disposed outside of the smoke box and to one side of the vertical longitudinal plane thereof, and a duct connecting said last named valve chest to another valve chest.

11. In a steam locomotive the combination of a boiler, a smoke box, a plurality of cylinders adapted to receive steam from the boiler, distribution valves for said cylinders, valve chests for said valves, a single passage leading from the boiler to one of said valve chests and adapted to conduct thereto a supply of steam for at least two valve chests, a throttle valve in said passage disposed outside of the smoke box and to one side of the vertical longitudinal plane thereof, and a duct connecting said last named valve chest with another valve chest.

12. In a steam locomotive the combination of a boiler, a smoke box, a plurality of cylinders adapted to receive live steam from the boiler, distribution valves for said cylinders, valve chests for said valves, a superheater, a passage connecting the boiler to the superheater, a passage connecting the superheater and one of said valve chests and adapted to conduct to such valve chest a supply of steam for at least two valve chests, a throttle valve in said last mentioned passage disposed outside of the smoke box and to one side of the vertical longitudinal plane thereof, and a duct connecting said last named valve chest with another valve chest.

13. In a steam locomotive the combination of a boiler, a smoke box, a superheater, a plurality of cylinders, distribution valves for controlling the flow of steam to said cylinders, valve chests for said valves, a single passage leading from the superheater to one of said valve chests and adapted to conduct a supply of steam for at least two cylinders to the last mentioned valve chest, a throttle valve in said passage disposed outside of the smoke box and to one side of the vertical longitudinal plane thereof, and a duct connecting said last named valve chest with another valve chest.

14. In a steam locomotive the combination of a boiler, a smoke box, a pair of cylinders, a pair of distribution valve chests, a passageway leading to one of said valve chests adapted to conduct a supply of steam thereto for both cylinders, a throttle valve in said passageway disposed outside of the smoke box and to one side of the longitudinal vertical plane thereof, and a duct connecting said last

named valve chest with the other valve chest to convey its portion of steam thereto.

15. In a steam locomotive having a valve chest disposed at each side thereof, a smoke box, a single passageway leading through the smoke box wall to one of the valve chests and adapted to conduct thereto an adequate supply of steam for both valve chests, a throttle valve in said passageway disposed outside of the smoke box and to one side of the longitudinal vertical plane thereof, and a supply passageway for one of the chests connected to the live steam chamber of the other chest for receiving live steam therefrom.

16. In a steam locomotive having a valve chest disposed at each side thereof, a cylinder saddle, a supply passageway for one of the chests passing through the cylinder saddle and connected to the live steam chamber of the other chest for receiving live steam therefrom, and a throttle valve mounted on the last mentioned chest for supplying live steam to said chest.

17. In a locomotive, the combination of a pair of side frame members, a smoke box, a pair of working cylinders disposed one at the outer side of each of the side frame members, a valve chest for each of the working cylinders, a passageway leading through the smoke box wall to one of the valve chests and adapted to convey a supply of steam for operating both working cylinders, a throttle valve in said passageway disposed outside of the smoke box and outwardly of one of the side frame members, and a passageway leading from one of the valve chests to the other valve chest for conveying the supply of working steam thereto.

18. In a locomotive, the combination of a pair of side frame members, a smoke box, a pair of working cylinders one on the outside of each of the side frame members, a valve chest for each of the working cylinders, a cylinder saddle, a passageway leading through the smoke box wall to one of the valve chests and adapted to convey a supply of steam for operating both working cylinders, a throttle valve in said passageway disposed outside of the smoke box and outwardly of one of the side frame members, and a passageway leading from one of the valve chests through the cylinder saddle to the other valve chest for conveying a supply of working steam thereto.

19. In a locomotive, the combination of a smoke box; a cylinder saddle; a steam chest on each side of the saddle; a steam passageway leading through the saddle and connecting one steam chest to the other, and a single steam passageway leading through the smoke box wall, communicating with one of the steam chests and having an inside diameter of sufficient size to permit the passage of the supply of steam for both steam chests.

20. In a locomotive, the combination of a smoke box; a cylinder saddle; a steam chest on each side of the saddle; a passageway leading through the saddle and connecting one steam chest to the other; a single steam passageway leading through the smoke box wall, communicating with one of the steam chests, and having an inside diameter of sufficient size to permit the passage of the supply of steam for both steam chests; and a throttle valve in the second mentioned passageway disposed outside of the smoke box wall.
